(57) **CLAIM**

The ornamental design for a nail lamp, as shown and described.

DESCRIPTION

FIG. 1 is a top view of a nail lamp showing my new design;
FIG. 2 is a bottom view thereof;
FIG. 3 is a left elevation view thereof;
FIG. 4 is a right elevation view thereof;
FIG. 5 is a front elevation view thereof;
FIG. 6 is a back elevation view thereof;
FIG. 7 is a perspective view thereof; and,
FIG. 8 is another perspective view thereof.
The broken lines in the drawings depict portions of the nail lamp that form no part of the claimed design.

1 Claim, 3 Drawing Sheets
